C. E. BENNETT

ARC GAP INSTALLATION

Filed April 7, 1922

UNITED STATES PATENT OFFICE.

CHARLES E. BENNETT, OF DECATUR, GEORGIA, ASSIGNOR TO BALT MANUFACTURING COMPANY, OF ATLANTA, GEORGIA, A CORPORATION OF GEORGIA.

ARC-GAP INSTALLATION.

Application filed April 7, 1922. Serial No. 550,425.

To all whom it may concern:

Be it known that I, CHARLES E. BENNETT, a citizen of the United States of America, residing at Decatur, in the county of De- 5 kalb and State of Georgia, have invented certain new and useful Improvements in Arc-Gap Installations, of which the following is a specification.

My invention relates to arc gap installations, and particularly to a gap terminal, the object of my invention being to provide a terminal having certain structural and functional features of advantage over those shown in my copending applications Serial 10 Nos. 402,569, filed August 10, 1920, patented January 1, 1924, No. 1,479,693, and 457,638, filed April 1, 1921.

In the accompanying drawings—

Fig. 1 is a side elevation partially in section of an arc gap terminal in which my invention is illustratively embodied; and 20 Fig. 2 is a rear elevation thereof.

The present terminal is adapted for use in an arc gap installation of the general 25 type indicated in my copending application above mentioned, or in any other appropriate installations. In such installations two terminals of like construction are generally employed, between which an arc is struck on a discharge through the gap circuit. Inasmuch as the terminals are alike, and an installation of the type mentioned is well known in the art, it suffices for the present purpose to illustrate but 30 one of the terminals.

As shown, the terminal is supported upon a rod 3, to which a circuit connection (not shown) may be established in any suitable fashion. The end of the rod is threaded, 40 and the metallic arcing contact 4 is screwed thereon. This contact may be of brass and is shaped to present a spherical face toward the gap. The hub 5 of the spider 6 is fixed by a set screw 7 on the rod 3 and carries a condenser ring 8 coaxial with the contact 4, but spaced outward radially therefrom. Cemented to the inner periphery of the ring at 9 is a dished insulator disc 10 presenting its convex face toward the arcing 45 contact 4—that is, toward the gap. The material of which the insulator disc is made may be alava, specially prepared porcelain, a suitable clay compound, or other highly refractory insulating material 50 which is porous or moisture permeable or

absorbent, while capable of receiving an arc without being pitted, or otherwise objectionably affected by the play of the arc thereon. At the axis of the insulator it is cupped to form a seat 11 for the contact 4.

Adjustably mounted on the rod 3 is a condenser plate 12 which may have a threaded hub 13 working on the threaded area of the rod. This plate may be over-weighted at one side by a boss 14 which serves to automatically maintain the plate by gravity in the position to which it is adjusted by screwing it on the rod. Preferably, the plate is of less diameter than the ring 8, and is also dished to conform substantially to the concave face of the insulator disc 10 so that it may be shifted on the rod from a position close to the disc 10 to a point considerably spaced therefrom. 65 It will be noted that the plate may be shifted from one side to the other of the plane of the condenser ring 8, and is thus 70 adjustable toward and from the gap and from the plate of the opposed cooperating 75 terminal of like construction.

An arcing horn 15 may be formed on the ring 8 and is flared away from the arc gap to assist in drawing out and breaking any arc that may be formed between the gap 80 terminals on a discharge through the gap circuit.

A terminal of this character possesses the important characteristic that at a given spacing of the terminals the gap rating 85 may be maintained practically uniform, not only under both wet and dry conditions of the gap at normal line voltage, but also under the same conditions when high frequency current is imposed on the line. In 90 fact the adjustment of the calibrating plate 9 toward and from the gap makes it possible to create a condition such that the arc-over at high frequency occurs at lower voltage than is necessary to cause an arc- 95 over at normal line frequency. In other words, the terminals may be set for dry condition under normal voltage at 60 cycles without danger of discharge at lower potentials in wet weather, while high frequency disturbances will span the gap even 100 before reaching the line voltage value.

By use of specially prepared and fired porous porcelain, a non-metallic surface is 105 presented to the rain drops or moisture, 110

which are instantly spread or absorbed entirely, preventing the retention of drops of water in the gap path. They then do not offer a point for flux concentration or make the gap distance shorter, as is the case where all-metal terminals are used. The importance of this characteristic can be appreciated especially with gaps of short spacing, where the presence of a drop of water 10 may so decrease the gap spacing as to cause the gap to break down at a very much less potential than that for which it is set, with the consequent unnecessary disturbance of service supplied by the circuit. Collection 15 of moisture in the form of drops, which are so often formed on metallic surfaces during foggy or damp weather, even when not raining, is impossible on porous porcelain and the present compensated impulse gap will, 20 therefore, not operate at normal line potential due to this cause.

By the use of highly refractory porous porcelain that is not affected by the high temperature of the arc, the pitting and 25 roughening of the surface that is always found in metal sphere or horn gaps after continued service, is also avoided, and the gap setting does not change its characteristics due to this roughening effect. With 30 metallic spheres it is not unusual, in short gaps, to find globules of melted metal that will represent 10% of the gap setting and reduce the normal break down potential by that amount. In the case of large spheres 35 with wide setting, the whole nature of the gap is changed by this roughening or pitting and instead of presenting a smooth polished surface to the charge, it soon becomes a series of points whose characteristic 40 break down potential for the gap is entirely different from that of the original sphere. This also has a tendency to fix the discharge continually at a certain point on the sphere, resulting eventually in actually burning 45 holes through the metal or destroying it entirely. This cannot occur with terminals of the present character.

The functioning of this device under wet 50 and dry conditions and impulse voltages is, as follows:

It is well known that at ordinary commercial frequencies, spheres of large diameter have a higher arc-over voltage for a given spacing than spheres of small diameter. In 55 a gap using terminals of the present type, when the porcelain is dry the discharge area is equal to that of the brass contact 11 in the center; but when it is wet, the porcelain in effect becomes a conductor instead of an insulator and thus increases the terminal area. In other words, this gap compensates for 60 weather conditions by this change in electrical characteristics, by automatically replacing the small spheres or points 4 with a 65 large spherical area of terminal (4, 8 and

10 combined) with no change in spacing, due to the permeation or absorption of moisture by the porcelain disc. These porcelain discs dry out almost immediately after rain, due to the drying effect of the electrostatic field always present at the gap when in service. While the moisture in the air manifestly decreases the arc-over voltage value in the usual horn or sphere gap, it increases the arc-over value of these gaps somewhat, 70 as the larger disc of wet porcelain is equivalent to and takes on the characteristics of a large sphere. Thus, a gap possessing the present terminals, has a higher break-down value when wet than when dry,—a most desirable function.

The present compensated impulse gap terminals make it possible to secure a gap that has an impulse break-down voltage less than that of ordinary sphere gaps under dry 80 weather conditions. It is on the approach of a storm, when the gaps are dry, that the greatest stresses are produced on equipment; the insulation being dry, it does not absorb or tend to dissipate transient potentials as 90 when all the insulators are wet. When wet, the dielectric resistance is lower and it is probable that impulses do not rise to the same potential value since there must be greater drainage through the dielectric 95 resistance.

The potential gradient over insulators, bushings, etc., is considerably less per unit of dielectric when wet, and they can stand greater shock, as each unit is not so likely 100 to be subjected to over stressing. It is necessary, therefore, that a perfect gap should function upon the slightest voltage ripple, due to switching surges, induced lightning 105 potentials, static or impulses of any sort during dry weather conditions.

The dry weather impulse potential curve of the present compensated impulse gap is considerably lower than the 60 cycle continuously applied break-down voltage, but can be adjusted in relative value. There are two 110 adjustments on the gap, which control the sensitiveness to impulse voltages. This is accomplished by revolving the adjusting metallic plates 12. When these plates are 115 moved closer to the porcelain discs, the sphere gap characteristics under impulse potentials are obtained and the gap is less sensitive to impulse or high frequency disturbances.

When the plates are close to the porcelain, the total flux across the gap has been largely increased because of the greater capacity brought about by bringing the two comparatively large metallic plates closer toward the center of the gap, and as the stress between the faces of the gap due to increased flux density has been increased, a greater 125 impulse potential is required for spark-over. In other words, the dielectric between the 130

electrodes, which includes the porcelain and air, is more uniformly stressed and, therefore, requires, as stated above, more potential to overstress or break down the gap.

5 By revolving the metallic plates away from the rear of the porcelain disc, I obtain a highly sensitive setting to impulse potentials, since when the metallic shields are moved back from the porcelain disc, the electrostatic capacity over the gap, and the flux about the center points has been increased. Therefore, the air around the points becomes more quickly overstressed, and as a result, a more instantaneous breakdown occurs and at a lower potential than with the other setting or that of a sphere.

10 The moving of the adjusting plates forward and backward from the porous porcelain disc, when wet, does not influence the high frequency or 60 cycle gap setting, the break-down then following very nearly the characteristics of a large sphere.

15 The successful gap and lightning arrester must have little time lag in order to protect apparatus from harm when subjected to impulse potentials.

20 An impulse voltage reflected upon electrical apparatus must have time and energy in order to rupture insulation. The destructive discharge through a dielectric requires not merely a sufficiently high voltage but a definite amount of energy. The destructive discharge does not occur instantly with its application, but a finite, though usually small, time elapses after the application of the voltage before the discharge occurs. During this time interval, energy must be supplied to the dielectric. As a result, therefore, the perfect gap and arrester combination should function at the beginning of this energy period in order to absorb and dissipate disruptive energy and prevent its entering the apparatus to be protected, if possible.

25 If this combination has a perceptible time lag, the impulse voltage will be applied to the dielectric for a part of a time at a given energy rate, and overstressing of the dielectric of the apparatus is sure to occur. Continual subjection to overstressing will cause injury and ultimate breakdown of such apparatus.

30 The present compensated impulse gap terminal fulfills all requirements of the ideal gap. It does not change its normal frequency breakdown value when wet or dry, and therefore can be given the close dry setting slightly above normal line potential with the assurance that it will not discharge at less than line potential when wet. It does not need protection by covering, and is set up in free air with nothing to restrict its ventilation.

35 It will discharge impulse or high fre-

quency disturbances at their inception, giving them the least chance to rise to destructive values. Its impulse value and its normal frequency value are capable of calibration independently of each other. It presents a fixed value to all discharges even under the heaviest rain fall usually experienced and needs no weather protection for this function.

I claim—

1. In an arc gap terminal, an arcing contact, an associated dished insulator coaxial therewith and presenting its convex face toward the gap, in combination with an adjustable condenser plate adapted to lie within the area of the insulator adjacent its concave face.

2. In an arc gap terminal, an arcing contact, an associated dished insulator coaxial therewith and presenting its convex face toward the gap, in combination with an adjustable condenser plate adapted to lie within the area of the insulator adjacent its concave face, said plate being dished to substantially conform to the curvature of the insulator.

3. In an arc gap terminal, an arcing contact, a conductor rod leading thereto, a metallic ring supported by the rod and coaxial with the arcing contact, together with an insulator supported by the ring and extending between the latter and the arcing contact.

4. In an arc gap terminal, an arcing contact, an associated insulator, a condenser ring radially spaced by said insulator from the contact, and a condenser plate adjustable across the plane of said ring, toward and from the arcing contact.

5. In an arc gap terminal, an arcing contact, an associated insulator, a condenser ring radially spaced by said insulator from the contact, and a condenser plate of less diameter than the ring and adjustable across the plane of the latter and within the ring, toward and from the arcing contact.

6. In an arc gap terminal, a conductor rod, an arcing contact at the end thereof, a spider mounted on the rod and spaced from said contact, an insulating disc supported by the spider and surrounding the arcing contact, together with a condenser plate adjustably mounted on said rod between the arcing contact and the spider mounting.

7. In an arc gap terminal, a threaded terminal rod, an arcing contact at the end of said rod, and a condenser plate screwing on said rod to adjust the same toward or from said contact.

8. In an arc gap terminal, a threaded terminal rod, an arcing contact at the end of said rod, and a condenser plate screwing on said rod to adjust the same toward

- or from said contact, together with an insulator interposed between said condenser plate and the gap.
9. In an arc gap terminal, a terminal rod, an arcing contact at the end thereof, a condenser ring radially spaced from the contact, a condenser plate, said ring and plate being electrically connected to the terminal rod, together with an insulator interposed between said arcing contact and said condenser ring and plate.
10. In an arc gap terminal, a terminal rod, an arcing contact at the end thereof, and a coaxial insulator having a convex face toward the contact, said face being recessed to afford a seat for the contact.
11. In an arc gap terminal, an arcing contact, and an adjustable condenser plate spaced from the contact, said plate having means for automatically maintaining the same at its adjusted spacing.
12. In an arc gap terminal, an arcing contact, and an adjustable condenser plate spaced from the contact, said plate having gravity actuated means for automatically maintaining the same at its adjusted spacing.
13. In an arc gap terminal, a conductor rod, an arcing contact at the end thereof, a spider mounted on the rod, a condenser ring carried by the spider and surrounding the arcing contact, together with a condenser plate adjustably mounted on said rod between the arcing contact and the spider mounting.
14. In an arc gap terminal, a conductor rod, an independent arcing contact secured at one end to the rod, a moisture-absorbent insulator mounted on the rod and surrounding the arcing contact, in combination with a condenser mounted on the rod and adjustable toward and from the arcing contact.
15. In an arc gap terminal, a conductor rod, an arcing contact at the end of the rod, and presenting a curved face toward the gap, in combination with a moisture-absorbent insulator mounted on the rod and peripherally surrounding the gap contact, said insulator presenting a curved face toward the gap, the radius of curvature being different from that of the gap contact.

In testimony whereof I have signed my name to this specification.

CHARLES E. BENNETT.
